SCORING AND BREAKING DEVICE FOR TILES

Edmund Engleke, North Bergen, N. J.

Application October 10, 1939, Serial No. 298,791

8 Claims. (Cl. 125—23)

The invention relates to improvements in devices for scoring and breaking tile, glass, and like vitreous material.

The principal object of the invention is to provide a device of this nature whereby tile and the like may be accurately and properly scored and then cut or broken with great precision.

Another object of the invention is to provide a relatively light-weight and compact device designed so as to be readily portable and one which is simple to operate.

Still another object of the invention is to provide a scoring and cutting device which shall accommodate extremely large tiles as well as small ones and which is, furthermore, suitable for cutting the tile diagonally and in various other fashions, as may be desired.

In carrying out the invention, there is provided on a suitable elongated supporting base a pivoted arm which carries a cutter slide movable longitudinally thereon, the slide bearing a cutter or scoring element whereby material located on the surface of the base may be scored. The arm is limited in its movement toward the base by contact of its free end with a buffer removably secured in the base at the end opposite the pivoted end of the said arm. Gauge means are arranged in and for adjustment transversely of the base to properly guide and hold a tile or the like for the scoring operation. To break a tile, particularly of the thinner types, provision is made for a breaker element which is fixed to the pivoted end of the arm for cooperation with an anvil mounted in the base for adjustment vertically toward and away from said breaker to accommodate the thickness of the tile to be broken, a tile being intended to be located therebetween and pressure exerted on the tile by pressing down on the said arm.

The nature of the invention, however, will best be understood when described in connection with the accompanying drawing, in which:

Fig. 1 is a plan view of the novel scoring and breaking device, and Fig. 2 is a side elevation thereof.

Fig. 3 is an elevation of the operating end of the device, and Fig. 4 is an elevation of the opposite end.

Figs. 5 and 6 are transverse sections taken on the line 5—5 and 6—6, respectively, Fig. 2 of the drawing, and looking in the direction of the arrows.

Referring to the drawing, 10 designates a hollow, rectangular base member with top surface 10' and side walls 11 and 11', and having

the feet or lugs 12 through which the member may be rested upon or affixed to a surface of a suitable support (not shown). At one end of the base there is provided an upstanding bifurcated bracket 13 to which is pivoted, as by means of an adjustable bolt, one end of an arm 14. The opposite end of this arm rests normally upon a buffer 15 removably attached to the opposite end of the base, as by being screwed therein.

Mounted on the said arm to slide along the same is a carriage or slider member 16 having a downwardly extending bifurcated arm 16' carrying a scoring element or die such as the wheel 17. This may be removably held therein by screw 18, on the shank of which it rotates, so that when a cutter becomes worn, it may readily be replaced. In order to prevent the slider 16 normally from slipping off the free end of the arm, there is screwed into the latter a cap member 19 which may be removed when it is desired to disassemble the device or remove the carriage.

At its pivoted end, the arm 14 has fixed thereto a breaker element 20 of any well-known design and having a longitudinal and shallow groove 25 20' along its median line. The breaker is arranged for cooperation with an anvil or breaker button 21 in the nature of a headed screw which is screwed into the surface 10' of the base and is adjustable vertically thereof toward and away 30 from the breaker element 20 to accommodate different thicknesses of tile. A set screw 22 directed from the side wall 11' of the base may be provided to fix the anvil member in its adjusted position.

35 To locate properly a tile 25 or the like for cutting, one or more gauge means are provided for adjustment transversely of the base. For example, the surface 10' of the base may be provided near its buffer end with a transverse groove 40 26 and is adapted to receive a bar 27 of a straight edge, provision being made for fixing the location of the straight edge as through a set screw 28 extending inwardly from the front of the base to engage the same. To accommodate 45 larger tile and to provide for cutting at various angles, a further gauging means may be provided as the rod 30 fitting through the base transversely thereof and oscillatable therein so that its finger or right-angle extension 31 may be elevated above the plane of the surface 10' of the base, as indicated by the dotted line position, Fig. 2 of the drawing. When the desired adjustment has been secured, this may be fixed by means of a set screw 32 passing into a lateral boss 33 from the base.

Further locations, particularly with respect to accommodating odd shapes and sizes of tile, may be secured by providing a series of sockets 35 and 36 in the supporting surface 10' of the base 10 and into which pins 37 may be fitted in the required position, such pins being readily removable from the socket when no longer required.

In operating the device, the same may be rested upon a suitable table or bench or, if necessary, secured thereto through the lugs 12. Thereupon the slider gauge or gauges are set for the desired cut and the tile placed on the table and positioned against the gauge. The slider is then moved along the arm toward the pivoted end of the arm and for scoring is drawn along the arm and over the tile with the scoring wheel 17 contacting the same to suitably score the tile surface. The tile may be placed between the breaker button or screw 21 and the breaker 20 with the scored line of break registering with the groove 20' in the under surface of the breaker, the screw 21 being adjusted so that the breaker is a slight distance above the surface of the tile. By pressing down on the arm, the tile will break along the line of scoring. In the case of extremely large tiles, the breakage may be effected by cracking the tile with a hammer, in well-known manner.

Numerous advantages are found in the use of the novel device over those heretofore proposed. For example, its light weight and compactness permits it to be carried in the usual tile layer's tool kit together with the customary other tools.

The simplicity of the mechanical action makes possible ease of operation and provides for accurate and rapid performance with clean and neat cut requiring no finishing operation.

Aside from the cutter, there is only one point where wear might occur, this being where the arm 14 is pivoted to the upstanding bracket 13. Any wear, however, is readily accommodated by taking up on the adjustable bolt on which the arm rocks.

In view of the length of the arm 14 which controls the breaking device, great power is afforded, and it is possible to break tile of a heavier gauge than has ever before been cut.

The provision of the buffer in addition to minimizing shock and noise prevents the cutting element or wheel from touching any part of the tool and thereby preserving it from any damage from this source.

The tool, moreover, can be used by a mechanic ordinarily working in awkward positions such as in small shower stalls as it may be fastened to the working board; and can be used, also, by either right- or left-handed mechanics with equal ease simply by supplying a gauge with reversely directed stop.

A clear working base is obtained simply by inverting the bar which removes the gauge stop and leaves the base clear to insert tiles of large sizes or odd shapes.

When one or more cuts are to be made, the tile to be cut is held in the hand, placed against the gauge stop, scored, inserted in the breaker, and cut, the desired cut portion being retained in the hand.

I claim:

1. Scoring and breaking device for tile or the like, comprising in combination an elongated base to support the tile, gauge means adjustable transversely thereof to overhang the same and means to secure the gauge means in adjusted

position, an arm pivotally supported above the base at its one end and extending over the gauge means, a buffer at its opposite end for limiting movement of the arm toward the base, a slide supported on and movable longitudinally of the arm, and a scoring element carried thereby, together with breaker means fixed to said arm.

2. Scoring and breaking device for tile or the like, comprising in combination an elongated base to support the tile, gauge means adjustable transversely thereof and means to secure the same in adjusted position, an arm pivotally supported above the base at its one end, a buffer at its opposite end for limiting movement of the arm toward the base, a slide supported on and movable longitudinally of the arm, a scoring element carried thereby, and a breaker element fixed to said arm at its pivoted end, together with a juxtaposed abutment or anvil extending upwardly from the base and adjustable vertically thereof toward and away from the breaker element.

3. Scoring and breaking device for tile or the like, comprising in combination a rectangular base affording a supporting surface for the tile and provided with a transverse groove across the surface at one end, a straight edge overhanging the base and slidable in the groove and means to secure the same in adjusted position, a bracket extending upwardly from the base at the end opposite the grooved portion, an arm pivotally supported in the bracket, a buffer removably mounted in the base at the end opposite the bracket to limit downward movement of the arm, and a score slide supported on and movable longitudinally of the arm, together with breaker means fixed to said arm.

4. Scoring and breaking device for tile or the like, comprising in combination a rectangular base affording a supporting surface for the tile and provided with a transverse groove across the surface at one end, a straight edge slidable in the groove and means to secure the same in adjusted position, a bracket extending upwardly from the base at the end opposite the grooved portion, an arm pivotally supported in the bracket, a buffer removably mounted in the base at the end opposite the bracket to limit downward movement of the arm, a slide supported on and movable longitudinally of the arm and means removably secured to the free end of the arm to prevent withdrawal of said slide, and a scoring element carried by the slide, together with breaker means fixed to said arm.

5. Scoring and breaking device for tile or the like, comprising in combination a rectangular base affording a supporting surface for the tile and provided with a transverse groove across the surface at one end, a straight edge slidable in the groove and means to secure the same in adjusted position, a rod passing through and adjustable transversely of the base intermediate its ends and having an arm projecting at right angles to the longitudinal axis of said rod, means to fix the rod to the base, a bracket extending upwardly from the base at the end opposite the grooved portion, an arm pivotally supported in the bracket, a buffer removably mounted in the base at the end opposite the bracket to limit downward movement of the arm, a slide supported on and movable longitudinally of the arm and means removably secured to the free end of the arm to prevent withdrawal of said slide, and a scoring element carried by the slide.

6. Scoring and breaking device for tile or the

like, comprising in combination a rectangular base affording a supporting surface for the tile and provided with a transverse groove across the surface at one end, a straight edge slidable in the groove and means to secure the same in adjusted position, a bracket extending upwardly from the base at the end opposite the grooved portion, an arm pivotally supported in the bracket, a buffer removably mounted in the base at the end opposite the bracket to limit downward movement of the arm, a slide supported on and movable longitudinally of the arm, a scoring element carried by the slide, and a breaker element fixed to said arm at the bracket end, together with a juxtaposed screw mounted in the base and affording an abutment or anvil extending upward toward the breaker element.

7. Scoring and breaking device for tile or the like, comprising in combination a rectangular base affording a supporting surface for the tile and provided with a transverse groove across the surface at one end, a straight edge slidable in the groove and means to secure the same in adjusted position, a rod passing through and adjustable transversely of the base intermediate its ends and having an arm projecting at right angles to the longitudinal axis of said rod, means to fix the rod to the base, a bracket extending upwardly from the base at the end opposite the grooved portion, an arm pivotally supported in the bracket, a buffer removably mounted in the base at the end opposite the bracket to limit downward movement of the arm, a slide supported on and movable longitudinally of the arm and means removably secured to the free end of 35

the arm to prevent withdrawal of said slide, a scoring element carried by the slide, a series of sockets in and extending transversely over the surface of the base, and pins removably mounted therein for supporting a tile along an edge.

8. Scoring and breaking device for tile or the like, comprising in combination a rectangular base affording a supporting surface for the tile and provided with a transverse groove across the surface at one end, a straight edge slidable in the groove and means to secure the same in adjusted position, a rod passing through and adjustable transversely of the base intermediate its ends and having an arm projecting at right angles to the longitudinal axis of said rod, means to fix the rod to the base, a bracket extending upwardly from the base at the end opposite the grooved portion, an arm pivotally supported in the bracket, a buffer removably mounted in the base at the end opposite the bracket to limit downward movement of the arm, a slide supported on and movable longitudinally of the arm and means removably secured to the free end of the arm to prevent withdrawal of said slide, a scoring element carried by the slide, a series of sockets in and extending transversely over the surface of the base, pins removably mounted therein for supporting a tile along an edge, and a breaker element fixed to said arm at the bracket end, together with a juxtaposed screw mounted in the base and affording an abutment or anvil extending upwardly toward the breaker element.

EDMUND ENGLEKE.
